UNITED STATES PATENT OFFICE.

JOHN C. BLEVNEY, OF LAWRENCE PARK, BRONXVILLE, NEW YORK.

RATCHET TOOL.

Original application filed June 27, 1921, Serial No. 440,382. Divided and this application filed July 28, 1921. Serial No. 488,079.

To all whom it may concern:

Be it known that I, JOHN C. BLEVNEY, a citizen of the United States, residing at Lawrence Park, Bronxville, in the county of Westchester and State of New York, have invented certain new and useful Improvements in Ratchet Tools; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in hand tools; and the invention has reference, more particularly, to a novel construction of ratchet tool of the kind shown in my former application for United States Letters-Patent, filed June 27th, 1921, Ser. No. 440,382, and of which this application is a division.

The present invention has for its principal object to provide a novel construction of ratchet mechanism and handle mounting therefor.

Other objects of the present invention, not at this time more particularly enumerated, will be clearly understood from the following detailed description of the same.

With the various objects of my present invention in view, the same consists, primarily, in the novel construction of ratchet tool hereinafter set forth; and, the invention consists, furthermore, in the novel arrangements and combinations of the various devices and parts, as well as in the details of the construction of the same, all of which will be hereinafter more fully described, and then finally embodied in the claims appended hereto.

The invention is clearly illustrated in the accompanying drawings, in which:—

Figure 1 is a front elevation of the novel ratchet tool, made according to and embodying the principles of the present invention, Figure 2 is a longitudinal vertical section of the same, taken on line 2—2 in said Figure 1; Figure 3 is a horizontal transverse section of the same, taken on line 3—3 in Figure 2; Figure 4 is another horizontal transverse section of the same, taken on line 4—4 in Figure 2 and showing the ratchet mechanism locked in neutral posi-

tion; Figure 5 is a view similar to that shown in Figure 4, but showing the ratchet mechanism set for right hand turning or driving of the tool with left hand release; while Figure 6 is another similar view, showing the ratchet mechanism set for left hand turning or driving of the tool with right hand release; and Figure 7 is a detail vertical transverse section, taken on line 7—7 in said Figure 3.

Figure 8 is a plan view of one of the housing plates which carry the ratchet mechanism.

Figure 9 is a perspective view of the ratchet pawl spring carrier and adjusting element.

Figure 10 is a perspective view of one of the ratchet pawls.

Similar characters of reference are employed in all of the above described views to indicate corresponding parts.

Referring now to said drawings, the reference character 1 indicates a tool handle, preferably made of cast metal, and suitably cored to provide an interior chamber 2. The lower end of the said handle terminates in a bearing portion 3 of suitable length and provided with a central longitudinal opening providing an axial bearing 4 for the shank of a tool to be operatively associated with said handle. The wall of said handle is essentially provided with a rectangular lateral opening 5, which, for the purpose of this description, may be said to be located in the front side of said handle, and intermediate its upper end and said bearing portion 3. In the opposite or rear side of said handle is located a vertical or longitudinal slot 6, the same being aligned with and corresponding in length to the height of said opening 5.

The reference characters 7 and 8 respectively indicate upper and lower housing plates, which are punched out of sheet metal of suitable gauge, and which are at the same time provided with the desired peripheral shape and with properly located and associated openings. In this respect each housing plate is provided with stop shoulders 9 at their outer ends, adapted to engage the side margins of the openings 5 of the handle when inserted therein to extend horizontally through the interior chamber 2 thereof; and at their inner ends the same are provided with tongues or lugs 10

10 which pass through the slot 6, whereupon their free projecting ends are turned or riveted over against the outer margins of the said slot, to thereby retain said housing plates in assembled relation to the handle, and secured against outward displacement or withdrawal through the opening 5. Each housing plate is provided with a central bearing opening 11; and forwardly spaced therefrom are a pair of laterally opposed ratchet-pawl trunnion bearing openings 12 of substantially triangular shape with their sides diverging toward their inner ends to provide for the desired play of said ratchet-pawls in a manner to be subsequently more fully described; and forwardly spaced from said bearing openings 12 is a centrally disposed laterally extending slot 13 having a plurality of keeper notches in its forward margin, to wit, a central or neutral keeper notch 14, a right hand ratchet drive keeper notch 15, and a left hand ratchet drive keeper notch 16, the purpose and operation of which in connection with other associated parts of the device, will be hereinafter more fully set forth.

When assembled with the handle 1, said housing plates 7 and 8 are disposed to extend horizontally through the interior chamber 2 thereof in vertically spaced relation, one above the other, and with their several openings, as above described respectively aligned vertically.

35 Disposed between said housing plates 7 and 8, and rotatably supported thereby by means of its hubs or journals 17 which are respectively journaled in the bearing openings 11 of said housing plates, is a toothed ratchet wheel 18 having a central axial opening 19, preferably of polygonal cross sectional shape; said axial opening 19 being in substantial vertical longitudinal alignment with said opening 4 of the bearing portion 3 of said handle.

The reference characters 20 and 21 respectively indicate a right hand drive ratchet pawl and a left hand drive ratchet pawl. Each ratchet pawl comprises a rectangular punching of sheet metal provided with flat oppositely projecting trunnions 22 extending respectively from their upper and lower edges. The trunnions of said right hand drive ratchet pawl 20 are journaled in the vertically aligned bearing openings 12 of said housing plates located to the right of said ratchet wheel 18; while the trunnions of said left hand drive ratchet pawl 21 are journaled in the vertically aligned bearing openings 12 of said housing plates located to the left of said ratchet wheel 18. The outer vertical edges of the trunnions of the respective ratchet pawls are fulcrumed in the outer converging ends of said bearing openings 12, and by reason of the

divergence of the sides of said bearing openings 12 toward the inner ends thereof, it will be apparent that the inner ends of the ratchet pawls are free to oscillate, or, in other words, are free to move toward and away from the ratchet wheel 18. The substantially triangular shape or outline of the bearing openings 12 is properly sized to provide a sufficient divergence to accommodate the desired amount of movement or swing of the ratchet pawls, and at the same time determines the limit of such movement. When the ratchet pawls are swung inwardly the inner ends of the same enter the notches intermediate the teeth of the ratchet wheel 18 so as to operatively engage the latter.

The operation of the ratchet pawls are controlled by a pawl spring mechanism. This pawl spring mechanism comprises a perpendicular carrier pin 23 upon which is supported a pawl spring comprised of two oppositely and laterally extending branches or leaves, to wit, the right-hand spring portion or leaf 24 and the left-hand spring portion or leaf 25, the one operatively engaging the ratchet pawl 20 and the other the ratchet pawl 21. The intermediate portion of the spring is formed with a loop 26 adapted to extend around and embrace the carrier pin. In order to hold the spring 95 in assembled and secured relation to the carrier pin and also to cover and protect the same I provide a guard plate 27, which is provided with inwardly bowed upper and lower loops 28 and an intermediate or central loop 29 which extends around and embraces the loop 26 of the spring as engaged with the carrier pin, while the loops 28 encircle the inner sides of the latter above and below the spring, thus holding the spring 105 against displacement. The oppositely extending wings or ends of said guard plate 27 extend over and protect the respective spring portions or leaves 24 and 25, but do not interfere with the operative flexing of said spring 110 portions or leaves when the same function.

The pawl spring mechanism thus constructed is mounted or supported by the housing plates 7 and 8 by entering the respective ends of said carrier pin 23 in the slots 13 115 of said respective housing plates, said carrier pin 23 being shiftable in the said slots for selective engagement with any pair of the keeper notches 14, 15 and 16 of said slots 13, according as it is required to dispose the 120 pawl spring mechanism to produce the desired functioning of the ratchet-pawls relative to the ratchet wheel.

The reference character 30 indicates a screw driver or other desired tool having a 125 shank 31. The upper end portion of the shank 31 is provided with a ratchet wheel coupling portion 32 of a cross sectional shape corresponding to the cross sectional shape of the axial opening 19 of said ratchet wheel, 130

whereby the tool shank may be secured in fixed relation to said ratchet wheel. The upper extremity of said shank 31 is provided with a tapered head 33 beneath which is provided an annular keeper groove or channel 34. To operatively associate the tool with the handle 1 and its ratchet wheel 18, the shank 31 thereof is inserted upwardly through the opening 4 of the bearing portion 3 until its coupling portion 32 enters through the axial opening 19 of the ratchet wheel 18. In order to retain the tool in associated and operative connection with the handle 1, there is provided a keeper spring device, the anchoring loop 35 of which is engaged around the lugs 10 of the housing plates 7 and 8, so as to be positioned between the wall of said handle and shoulders 36 provided at the juncture of said lugs 10 with the main portion of the said housing plates. Extending horizontally from said anchoring loop 35 are a pair of spring keeper arms 37, which terminate in upwardly projecting finger pieces 38. As the tapered head 33 of the tool 25 shank, when the latter is passed into engaged relation to said ratchet wheel, emerges from the upper end of the ratchet wheel, the same passes between said spring keeper arms 37 thereby spreading the same until they are 30 sprung over said head so as to enter into said annular keeper groove or channel 34, whereupon said spring arms become engaged beneath said head thereby retaining said tool against removal from the handle and its ratchet wheel. When it is desired to remove said tool from the handle, the operator merely inserts a finger between the finger pieces 38 (the walls of said handle opposite said finger pieces 38 being provided with a 35 suitably formed admission opening 39 for such purpose), whereupon the same are spread apart and such spreading movement is communicated to the spring keeper arms 37 so that the same are removed from the keeper groove or channel 34 and from under the head 33, so that the tool is thereby released for withdrawal from the handle and its ratchet wheel.

Having thus described the detail construction of my invention I will now briefly describe the manner of its adjustment and operation in use. First, if it is desired to lock the handle and tool together so that turning movements of the former to either the right or left will be transmitted to the tool, the pawl spring mechanism is set in a so called neutral position so that both ratchet pawls 20 and 21 are engaged with the ratchet wheel. This arrangement of the parts is 50 illustrated in Figures 1 to 4 inclusive and in Figure 7, and as an inspection of said Figures will disclose, the carrier pin 23 is disposed in the neutral keeper notch 14 or in normal central position whereby the pawl spring is centrally positioned so that the 55 spring leaf 24 engages the ratchet-pawl 20 at a point inwardly positioned relative to its fulcrum, and the spring leaf 25 engages the ratchet-pawl 21 at a point inwardly positioned relative to the latter's fulcrum, where- 70 by the respective ratchet-pawls are both inwardly swung to operatively and oppositely engage the ratchet wheel 18 whereby the handle is locked against turning independently of the ratchet-wheel and tool connected therewith in both directions, and consequently the tool may be turned by hand in either direction, viz. to the right or left. 75

Secondly, if it is desired to so relate the handle to the tool that only a turning movement of the former to the right will be transmitted to the tool, (as, for example, in driving a wood-screw,) while an independent turning movement of the handle to the left not transmitted to the tool is provided for, 80 then the pawl spring mechanism is set to operatively engage the right hand drive ratchet pawl 20 with the ratchet wheel 18, while at the same time releasing the left hand drive ratchet pawl 21 from operative 85 engagement with said ratchet wheel. This arrangement of the parts is illustrated in Figure 5 of the drawings, and is accomplished by pressing inwardly the guard-plate 27 and carrier pin 23 to release the latter 90 from the neutral keeper notch 14, whereby the same may be shifted through the slots 13 into engagement with the keeper notches 15. This movement shifts the pawl spring laterally, so that while the spring leaf 24 still engages the right hand drive ratchet pawl 20 at a point inwardly positioned relative to its fulcrum, whereby the same is retained in operative engagement with the ratchet wheel 18, the other spring leaf 25 is shifted to engage the left hand drive ratchet-pawl 21 at a point outwardly positioned relative to the latter's fulcrum, whereby the pressure of the spring tends to rock the pawl on its fulcrum to swing its inner operative end away from the ratchet wheel 18. It thus follows that a 100 turning movement of the handle 1 to the right is transmitted through the right hand drive ratchet-pawl 20 to the ratchet wheel 18 and thence to the tool, while a turning movement of the handle to the left fails to engage the outwardly held left hand drive ratchet-pawl 21 with the ratchet-wheel, and consequently the latter and the tool remains stationary, and the right hand drive ratchet-pawl 20, being yieldingly pressed inward by the spring leaf 24, rides over the teeth of the ratchet-wheel, until right hand turning movement of the handle is resumed. 110

Thirdly, if it is desired to so relate the handle to the tool that only a turning movement of the former to the left will be transmitted to the tool, (as, for example, in withdrawing a wood screw,) while an independent movement of the handle to the right is 115 120 125 130

provided for, then the pawl spring mechanism is set to operatively engage the left hand drive ratchet pawl 21 with the ratchet wheel 18, while at the same time releasing 5 the right hand drive ratchet-pawl 20 from operative engagement with said ratchet wheel.

My novel construction of ratchet mechanism may be made stronger and larger, than 10 is usual in tools of this character, by reason of its location within the comparatively roomy space of the hollow handle. Another 15 advantage of the novel ratchet mechanism and means for mounting the same, lies in the fact that close and accurate machining and fitting of the parts is unnecessary, since the housing plates may be loosely enough fitted within the handle to allow sufficient lateral play whereby the insertion into the 20 handle of the shank of the tool, even where the latter is not perfectly true axially, will engage and operatively connect the ratchet wheel therewith.

It will be understood that various kinds 25 of shank tools or tool chuck shanks may be employed with the novel handle and ratchet mechanism, and that I do not limit myself to the screw driver tool shown in the drawings.

30 I am aware that some changes may be made in the arrangements and combinations of the various devices and parts, as well as in the details of the construction of the same, without departing from the scope 35 of my invention as set forth in the foregoing specification, and as defined in the appended claims. Hence, I do not limit my invention to the exact arrangements and combinations of the various devices and 40 parts as described in said specification, nor do I confine myself to the exact details of the construction of said parts as illustrated in the accompanying drawings.

I claim:—

- 45 1. In a ratchet tool, a ratchet wheel with which a tool is engaged, a pair of opposed flat pawls having flat trunnions intermediate their ends, bearing means for said pawls having substantially triangular bearing 50 openings engaging said trunnions to fulcrum the latter on their outer vertical edges, and means for holding said pawls in variously adjusted positions for desired cooperation with said ratchet wheel.
- 55 2. In a ratchet tool, a hollow handle member, a pair of horizontal housing plates supported within said handle member one above the other, a ratchet wheel journaled between said housing plates adapted for connection 60 with a tool member, a pair of opposed ratchet pawls having flat trunnions, said housing plates having substantially triangular bearing openings to receive said pawl trunnions whereby the outer edges of said 65 trunnions are fulcrumed in the acute ends of said bearing openings to permit the inner ends of said pawls to swing toward

of said bearing openings to permit the inner ends of said pawls to swing toward and away from said ratchet wheel, an adjustable pawl spring means supported by said housing plates, and said handle member having a side 70 opening giving access to said pawl spring means to permit manipulation thereof.

3. In a ratchet tool, a hollow handle member, a pair of horizontal housing plates supported within said handle member one above 75 the other, a ratchet wheel journaled between said housing plates adapted for connection with a tool member, a pair of opposed ratchet pawls having flat trunnions, said housing plates having substantially triangular bearing 80 openings to receive said pawl trunnions whereby the outer edges of said trunnions are fulcrumed in the acute ends of said bearing openings to permit the inner ends of said pawls to swing toward and 85 away from said ratchet wheel, a carrier pin, a pawl spring fixed to said carrier pin, said pawl spring having oppositely extending spring leaves respectively engageable with 90 said ratchet pawls, said housing plates having slots in which the ends of said carrier pin are received, said slot having keeper notches selectively engageable by said carrier pin to hold said pawl spring in desired 95 adjusted position, and said handle member having a side opening giving access to said pawl spring device to permit manipulation thereof.

4. In a ratchet tool, a hollow handle member having a side opening, a pair of horizontal housing plates adapted to be inserted through said side opening to position the same within said handle member one above the other, means for securing said housing plates to prevent withdrawal thereof, a ratchet wheel journaled between said housing 100 plates adapted for connection with a tool member, and an adjustable ratchet pawl mechanism supported by said housing plates adjacent to said side opening of said handle 105 member.

5. In a ratchet tool, a hollow handle member having a side opening, a pair of horizontal housing plates adapted to be inserted through said side opening to position the same within said handle member one above the other, means connected with the inner ends of said housing plates for riveting the same to the wall of said handle member opposite said side opening to prevent withdrawal thereof, a ratchet wheel journaled between said housing plates adapted for connection with a tool member, a pair of opposed ratchet pawls having flat trunnions, said housing plates having substantially triangular bearing 115 openings to receive said pawl trunnions whereby the outer edges of said trunnions are fulcrumed in the acute ends of said bearing openings to permit the inner ends of said pawls to swing toward 120

125

- or away from said ratchet wheel, an adjustable pawl spring means supported by said housing plates adjacent to said side opening of said handle member.
- 5 6. In a ratchet tool, a hollow handle member having a side opening, a pair of horizontal housing plates adapted to be inserted through said side opening to position the same within said handle member one above the other, means connected with the inner ends of said housing plates for riveting the same to the wall of said handle member opposite said side opening to prevent withdrawal thereof, a ratchet wheel journaled between said housing plates adapted for connection with a tool member, a pair of opposed ratchet pawls having flat trunnions, said housing plates having substantially triangular bearing openings to receive said pawl trunnions whereby the outer edges of said trunnions are fulcrumed in the acute ends of said bearing openings to permit the inner ends of said pawls to swing toward or away from said ratchet wheel, a carrier pin, a pawl spring having oppositely directed arms respectively engageable with said pawls, means securing said pawl spring to said carrier pin, said housing plates having slots in which the ends of said carrier pin are received, and said slot having keeper notches selectively engageable by said carrier pin to hold said pawl spring in desired adjusted position, said pawl spring mechanism being located within said side opening of said handle member and accessible therethrough for manipulation.
- 10 15 20

In testimony that I claim the invention set forth above I have hereunto set my hand this 20th day of July, 1921.

JOHN C. BLEVNEY.
